UNITED STATES PATENT OFFICE.

WILLIAM W. McCALLIP, OF COLUMBUS, OHIO.

MACHINE FOR WEAVING AND SELVAGING DIAMOND-MESH WIRE FABRIC.

No. 800,469.

Specification of Letters Patent.

Patented Sept. 26, 1905.

Application filed September 24, 1903, Serial No. 174,468.

To all whom it may concern:

Be it known that I, WILLIAM W. McCALLIP, a citizen of the United States, residing at Columbus, in the county of Franklin and State of Ohio, have invented certain new and useful Improvements in Machines for Weaving and Selvaging Diamond-Mesh Wire Fabric; and I do hereby declare the following to be a full, clear, and exact description of the invention, such as will enable others skilled in the art to which it appertains to make and use the same.

This invention relates to machines for weaving wire fabric of the kind known as "diamond-mesh," because the diagonals of the mesh stand in the direction of the length and width of the fabric although the mesh may, in fact, be of square form.

In the particular kind of machine to which the present invention relates there is a frame containing two angularly-arranged pairs of parallel rotary shafts, each pair carrying fingers or teeth adapted as the shafts are revolved to elevate and depress alternate wires to form sheds through which the weft-wires are inserted, the fabric being intermittently moved from the position where every other wire is raised to a position where said wires are depressed to successively form new sheds into which the weft-wires are inserted to make the fabric.

The present invention consists, first, in the provision of improved devices for guiding the wires inserted to manufacture the fabric; second, in improved means for feeding and holding the fabric in proper position while being woven; third, in improved means for beating up or forcing into proper position in the fabric the weft-wires; fourth, in the provision of an improved wire elevator and depressors adapted to reach wires that have passed beyond the range of the regular elevators and depressors so that the fabric will be properly woven at its edge as well as in the body thereof; fifth, in improved devices for reeling or rolling up the fabric as it comes from the weaving-machine, and, sixth, in the provision of means for making a selvage in the fabric.

In the accompanying drawings, Figure 1 is a general plan view of the machine, some parts being omitted. Fig. 2 is an elevational view of the right-hand side of the machine,

some parts being omitted. Fig. 2^a is a detail in perspective of the shed-forming and beating-up devices. Fig. 3 is a vertical sectional view on the line *u u*, Fig. 4, to show the wire-guiding and beating-up devices. Fig. 4 is an elevation of the same viewed from the fabric side. Fig. 5 is a plan view on a larger scale than appears in Fig. 1 of the selvage-applying mechanism. Fig. 6 is an elevation of the same viewed from the fabric side. Fig. 7 is a vertical section on the line *v v*, Fig. 6, looking to the right. Fig. 8 is a section on the line *w w*, Fig. 6, showing the wire-bender looking to the right. Fig. 9 is a side view of the rack and pinion for operating the bender shown in Fig. 8. Fig. 10 is a sectional view illustrating in edge view the improved elevators and depressors. Fig. 11 is a plan view of the same, and Fig. 12 is an elevational view showing the fabric reeling or rolling devices.

Like characters of reference in the several views designate corresponding parts.

1 designates an upper eccentric-shaft, to which is hung and by which is operated a bar 2 to contain the wire-depressing fingers 3, and 1^a designates a similar shaft, to which is attached a bar 2^a, containing wire-elevating teeth 3^a. The two shafts 1 and 1^a are connected by a sprocket-chain 1^b, (see Fig. 2,) and all four of the shafts are driven from a belt-wheel 1^c, (see Fig. 1,) operating the shaft 1^d, the latter having miter-gears engaging similar gears on the shaft 1^a. There are, as before indicated, two pairs of shafts 1 and 1^a, each pair operating two sets or series of teeth, the shafts being arranged at right angles to each other, as indicated in Fig. 1, so that as the fabric is moved in the process of weaving each of two series of alternate wires at each side of the fabric is first elevated and then depressed to form a shed, through which the strands that go to make up the fabric are inserted. The teeth for elevating and depressing the wires are shown herein to be of the hollow variety—that is, provided with a horizontal strand-guiding eye open at one side and toward the fabric. To prevent the strand-wire being inserted from turning aside out of its path through said eyes, I provide several or all of the eyes with beards or covers shaped like a sector of the body of the guiding-eye yieldingly held over the openings at the sides.

- The beards are designated 4, (see Figs. 3 and 4,) and they can be mounted on a rod 4^a, hinged in ears 4^b on the bars 2 and 2^a. A spring 4^c is provided to hold the beards against the openings of the strand-guiding eyes, so that as the fabric is fed the beards will yield and allow the fabric to pass to its next position. After a pair of wires is inserted the whole body of the fabric is fed or moved to a new position. To properly effect this, I now provide fabric-moving devices consisting of wheels or rollers of the kind indicated at 5, having their peripheries furnished with pyramidal projections 5^a, adapted to fit in the mesh of the fabric, said fabric-feeding wheels or rollers being mounted on a main intermittently-driven shaft 6 and auxiliary shafts 6^a, connected with and driven by the main shaft through sprocket-chains or other gearing.
- The main shaft 6 is intermittently driven by the eccentric-shafts 1^a, appropriate and well-understood gearing being interposed for effecting such intermittent motion. I have discovered that it is particularly important that the fabric within the angle between the shafts 1 be held from distention laterally or longitudinally, otherwise there is likely to be irregularity in the weaving and buckling of the fabric. Hence I locate one or more of the wheels or rollers 5 within said angle, as seen in Fig. 1.
- The improved means for moving or "beating" up the inserted wires consists of a beater-arm 7, secured to a shaft 7^a, journaled in brackets 7^b, projecting from the side of the bar 2^a. Keyed to said shaft 7^a is a tappet-arm 7^c and a tappet-arm 7^d, projecting in opposite directions from the shaft. The tappet-arm 7^c is operated by a crank-arm 7^e on the shaft 1^a to throw the beater-arm 7 inward toward the fabric, and thus move or "beat" the inserted or weft wire up to its proper position in the fabric. When the crank-arm 7^e has passed the tappet-arm 7^c, the bar 2^a is drawn downward by the operation of the eccentric-shaft and the tappet-arm 7^d brought against the upper end of the bar 7^f, thus returning the beater to its original position between the teeth.
- I have further discovered that it will sometimes happen that the wires along the edge of the fabric are not regularly interwoven. This is because the wire elevating and depressing teeth as heretofore constructed do not reach the ends of the wires after they pass to a point out of the vertical plane of the bars 2 and 2^a. This point I have indicated at A, Fig. 1. To reach such wires, I now propose to place in the bars 2 and 2^a teeth, the operative ends of which lie beyond the vertical plane of the bars 2 and 2^a, as indicated in Figs. 10 and 11. These added teeth are designated 3^b and 3^c, and they are

preferably composed of two parts, a shank and a blade, the shank being attached to the bars 2 and 2^a and the blades adjustable horizontally on the shanks at right angles to said bars, so that the operative ends may be set to act at the most favorable points on the wires to depress and elevate them. This adjustability of the teeth 3^b and 3^c is advantageous because the fabric to be woven will vary in the size of mesh as well as in the strength and character of wire used.

As fast as the fabric is woven it is important that it be properly reeled or rolled up, so I propose to provide at the rear of the machine a frame 8, containing a shaft 8^a, having thereon rollers like the rolls 5 for engaging the mesh at the under side of the fabric as it comes from the machine, and a parallel shaft 8^b, containing a plane roller 8^c, yieldingly held by a spring 8^d against the inner side of the cylinder of fabric. To keep the roll or cylinder of fabric from falling over, I provide a roller 9, journaled in a frame having side bars 9^a pivoted at 9^b to the side of the frame 8 and having suitable means for holding it in position.

We come now to the apparatus for applying a selvage to the fabric. This apparatus comprises, generally stated, first, means for taking a pair of the crossed ends of two wires at the edge of the fabric and bending them horizontally, so that they stand parallel to each other; second, means for bending them upward and inward over the selvage wire, and, third, means for looping or clenching them down around the selvage wire.

Referring to Figs. 5 and 6, the character 10 designates a frame which is adjustably secured to and reciprocated with the bar 2, and 11 designates a frame that is similarly secured to and reciprocated with the bar 2^a. These two frames are arranged on the bars 2 and 2^a, so that they stand in approximately the vertical plane of the edge of the fabric as it progresses through the machine, as indicated in Fig. 1. On the inner face of the frame 10 are two symmetrically-shaped sliding plates 10^a, having their lower ends formed with wire-bending tongues 10^b. The plates 10^a are connected by links 10^c with the opposite sides of a disk 10^d, centrally journaled in the frame 10. The outer end of the journal of the disk 10^d has secured to it a crank-arm 10^e, that is intermittently struck by the cam or inclined end 1^f of an arm 1^g on the shaft 1, so that the wire-bending tongues 10^b are brought toward each other to bend the ends of the wires together. A spring 10^g between the sliding plates 10^a will serve to separate the tongues after the cam 1^f has passed the crank-arm 10^e. During this bending operation the wires in the body of the fabric are kept rigid by means of a grooved vise mem-

ber 10^b, working in conjunction with a similarly-grooved vise member 11^a on the frame 11. When the tongues 10^b are descending into place on each side of a pair of crossed ends 5 of wires, a bending-finger 11^a on a shaft 11^b, journaled in the frame 11, is given a partial rotation by a rack-bar 10ⁱ on the frame 10, turning a pinion 11^c on the shaft 11^b. This finger 11^a turns the paralleled ends of the 10 wires up into a position, as seen in Fig. 8, where they can be bent down around the selvage-wire 12 by means of a vertically-acting die 10^j, working in conjunction with a bed member 11ⁱ on the frame 10. It will be observed that each of these operations takes 15 place during a single revolution of the shafts 1 and 1^a.

The operation briefly is as follows: For convenience in practice, a small piece of fabric 20 for a "starter" is first made up by hand. This piece is put into the machine so that the longer unwoven ends lie alternately under the teeth 3 and above the teeth 3^a. With the wires so placed and the eccentricities of the shafts 1 and 25 1^a in the position seen in Fig. 3, a shed is formed through which new strands are inserted by the attendant. By the application of power the shafts 1 and 1^a are then each given a complete revolution, during which the several operations hereinbefore referred to are 30 performed. The beating-up operation and the operation of the benders 10^b at the selvage take place first—that is, during the first portion of the revolution of the shafts 1 and 1^a. The fabric-feeding operation follows these 35 operations or while the bars 2 and 2^a are sufficiently separated from each other to allow free movement of the fabric. When the bars 2 and 2^a approach each other—that is, during the final portion of the revolution of the 40 shafts 1 and 1^a—the bending-up and the bending-down operations at the selvage take place and new shed formed.

Modifications in the forms of the parts 45 shown and described can be made without departing from the substance of the invention.

What I claim, and desire to secure by Letters Patent, is—

1. In a machine for weaving diamond-mesh 50 wire fabric, a wire elevating or depressing tooth having a guiding-eye open at its side, combined with a movable cover or beard.

2. In a machine for weaving diamond-mesh 55 wire fabric, a wire elevating or depressing tooth having a guiding-eye open at its side, combined with a movable cover or beard, and means for yieldingly holding said cover or beard over said opening.

3. In a machine of the kind described for 60 weaving diamond-mesh wire fabric, means for engaging and holding the fabric located within the angle between the lines where the weft-wires are inserted.

4. In a machine of the kind described for weaving diamond-mesh wire fabric, devices for holding the fabric located within the angle between the lines where the weft-wires are inserted, devices for holding the fabric outside said angle, and means for simultaneously operating both said holding devices to feed or move the fabric. 65

5. In a machine for weaving diamond-mesh wire fabric of the kind described, a beater comprising a beater-arm, a shaft on which the same is mounted, a tappet operative to throw 75 said beater-arm inward toward the fabric and a tappet operative to throw said beater outward from the fabric.

6. In a machine for weaving diamond-mesh wire fabric of the kind described, a wire elevating or depressing tooth projecting beyond the range of the regular wire elevating or depressing teeth. 80

7. In a machine for weaving diamond-mesh fabric of the kind described, a horizontally-adjustable wire elevating or depressing tooth adapted to project beyond the range of the regular wire elevating or depressing teeth. 85

8. In a machine for weaving diamond-mesh wire fabric of the kind described, means for reeling the woven fabric into cylindric form comprising a toothed roller to engage the under side of the fabric and a plain pressure-roller to engage the inner side of the fabric. 90

9. In a machine for weaving diamond-mesh wire fabric of the kind described, means for reeling the woven fabric into cylindric form comprising rolls to engage the outer and inner sides of the lower portion of the cylinder, and a roller to support the cylinder at its side. 95

10. In a machine for weaving diamond-mesh wire fabric, apparatus for applying a selvage thereto comprising means for bending to parallel position the crossed wires at the edge of the fabric and means for turning said parallel 105 wires around a selvage-wire.

11. In a machine for weaving diamond-mesh wire fabric, apparatus for applying a selvage thereto comprising means for bending to parallel position in a horizontal plane the crossed wires at the edge of the fabric, means for partially bending said parallel wires vertically and means for pressing said wires onto a selvage-wire. 110

12. Apparatus for applying a selvage to diamond-mesh wire fabric comprising means for bending to parallel position the crossed wires at the edge of the fabric, and means for turning the paralleled wires around a selvage-wire. 115

13. Apparatus for applying a selvage to diamond-mesh wire fabric comprising means for bending to parallel position the crossed wires at the edge of the fabric, means for holding fixed the adjacent portions of the 125 fabric while said crossed wires are being bent,

and means for turning said paralleled wires around a selvage-wire.

14. In a machine for weaving diamond-mesh wire fabric, means for intermittently feeding the woven fabric, and means for securing a selvage wire or rod to the edge of said fabric consisting of devices automatically operative in the intervals between the fabric-feeding operations adapted to bend the terminals of

the wires composing the fabric over said 10 selvage-wire, substantially as described.

In testimony whereof I affix my signature in presence of two witnesses.

WILLIAM W. McCALLIP.
